United States Patent Office

Des. 188,297
Patented June 28, 1960

188,297

BOTTLE

William W. Pedrick III, Lancaster Township, Lancaster County, Pa., assignor to Armstrong Cork Company, Lancaster, Pa., a corporation of Pennsylvania

Filed Apr. 13, 1959, Ser. No. 55,486

Term of patent 14 years

(Cl. D58—8)

The dominant features of my design are shown in full lines in the drawing.

I claim:

The ornamental design for a bottle, substantially as shown and described.
